UNITED STATES PATENT OFFICE.

CHARLES W. LOVELL, OF BROOKLYN, NEW YORK.

PAPER-CUTTING MACHINE.

1,308,852.

Specification of Letters Patent.

Patented July 8, 1919.

Application filed March 19, 1919. Serial No. 283,565.

To all whom it may concern:

Be it known that I, CHARLES W. LOVELL, a citizen of the United States, and resident of Brooklyn, in the county of Kings and State 5 of New York, have invented certain new and useful Improvements in Paper-Cutting Machines, of which the following is a specification.

The invention relates to improvements in 10 paper-cutting machines, commonly known as "lever paper cutters," in which hand power is employed for reciprocating a knife in a shearing manner to cut a pile of sheets against a cutting-block.

15 Ordinarily, in the operation of devices of this character, the cutting movement of the knife is stopped by its engagement with the opposing relatively soft wood-cutting block, thereby causing a penetration of the latter 20 which gradually increases under repeated actions to form an abnormal recess in the block of undesirable depth. As the depth of the recess increases, the walls thereof exert a correspondingly greater frictional 25 resistance to the withdrawal of the knife in its upward movement from the block, the resistance thus offered being sufficient under hand operation to considerably limit the power and capacity of the machine. Furthermore, the recess thus formed in the 30 block offers a lateral clearance space for the beveled cutting edge of the knife, which in its action tends to deflect or spread the lowermost sheets of the pile into the recess 35 and thereby sever the work unevenly. To overcome these difficulties in a measure, it is common practice to frequently shift the position of the block and present a new cutting surface for the knife, or to renew the 40 block entirely, both means being attended with loss of time and expense.

The object of the present invention is to provide means for overcoming the above-mentioned disadvantages by limiting the extent 45 of penetration or recess of the block to a predetermined depth necessary for a clean cutting action on the work, and to maintain such depth by stopping the cutting movement of the knife independently of the resistance offered by the block. A further object provides convenient means for adjusting this downward movement, or extent of penetration, without disturbing the adjustment of the knife with respect to its connected knife-stock. And the invention also provides means for absorbing the shock due

to suddenly arresting the movement of the cutting parts under excessively or carelessly applied manual operating force.

In describing the invention in detail, reference is had to the accompanying drawings, forming a part of this specification, and wherein like characters of reference are used to designate corresponding parts throughout the several views and in which:

Figure 1 is a front elevation of a paper-cutting machine shown with the improved stop attached thereon; Fig. 2, a transverse view of the machine, with certain of its parts shown in section; and Fig. 3 is an enlarged detail view of the stop.

In the drawings, numerals 1 and 2 designate the main frames of the machine, provided with the lower cross-brace 3 and the upper brace or yoke 4, and between said braces is secured the fixed work-table 5. The frames are provided in the usual manner with ways to slidably receive the knife-stock 6 and the clamp-head 7, the latter being constructed and operated in well-known manner, the screw 8 and the hand-wheel 9 indicating the operating means. The cutting-knife 10 is detachably secured by screws in conventional manner to the knife-stock 6, which is pivotally suspended by the link-bars 11 and 12, the latter having an extended arm 13, engaged by one end of a connection-rod 14, the opposite end thereof being pivotally connected to the short arm 15 of an actuating hand-lever 16, the latter being fixedly connected to the arm and mounted for rocking movement on the pin 17, carried by the brace 3. The several parts above described constitute a well-known form of hand lever paper cutter, in which by means of the hand lever the knife 10 in its cutting action is forced against the cutting block 18.

For limiting the downward or cutting movement of the knife, a base 19 is provided, having at one end a hinge connection 20, in which is pivotally mounted a stop-plate 21, the movement of which about its pivotal point is controlled by the adjustment screw 22, one end thereof being hinged to the plate 19 while the opposite end extends through a recessed perforation in the base and is provided with an adjusting nut 23. A helical compression spring 24 surrounds the adjustment screw, extending into the recessed portion and bearing at one end against the interior shoulder of the recess, the opposite or

- outer end of the spring bearing against the stop-plate, or the extension thereof that engages the hinged end of the adjustment screw. The spring serves to project or outwardly urge the stop-plate 21 from the base 19 in opposition to the adjusting nut 23, and by adjusting the latter, the projecting movement of the plate may be readily varied. The base 19 is further provided with a threaded perforation engaged by a stop-screw 25, having a lock-nut 26, arranged to adjustably hold the screw at any desired position therein, whereby the projecting end of the screw is adapted to engage and adjustably limit the inward movement of the stop-plate. The base 19 is also provided with connection holes 27, through which screws 28 pass and serve to attach the base to the knife-stock 6 of the machine, the position thereon being adjacent the main frame 1, and with which the stop-plate 21 of the base engages as the knife-stock and knife in their joint downward and lateral shearing movement reach their lowermost cutting position, the said engagement operating to swing the stop-plate in opposition to the yielding spring 24 against the end of the stop-screw 25, whereupon the movement of the cutting-knife is arrested.
- It will be obvious that by adjusting the stop-screw with respect to the stop-plate, the downward or cutting movement of the knife and the depth of its penetration into the cutting-block may be readily varied to insure a complete cutting action on the work. Also it will be evident that the yielding action of the spring will serve to reduce or overcome the shock due to the sudden stoppage of the knife.
- What I claim as my invention and desire to secure by Letters Patent, is:
1. In a paper-cutting machine, the combination of a knife-stock mounted for movement in the fixed frame of the machine and arranged for manual operation, a cutting-knife for said knife-stock, a cutting-block of relatively soft material arranged for penetration by said knife, a base fixed to said knife-stock adjacent the fixed frame of the machine, a stop-plate movably mounted on said base and adapted to engage the fixed frame of the machine, and means carried by said base for adjusting the movement of said stop-plate, whereby the cutting movement of the knife is variably limited with respect to the cutting-block.
  2. In a paper-cutting machine, the combination of a knife-stock mounted for movement in the fixed frame of the machine and arranged for manual operation, a cutting-knife for said knife-stock, a cutting-block of relatively soft material arranged for penetration by said knife, a base fixed to said knife-stock adjacent the fixed frame of the machine, a stop-plate movably mounted on said base and adapted to engage the fixed frame of the machine, means carried by said base for adjusting the movement of said stop-plate, and a spring interposed between said base and stop-plate to yieldingly arrest the cutting movement of said knife.
  3. In a paper-cutting machine, the combination of a knife-stock mounted for movement in the fixed frame of the machine and arranged for manual operation, a cutting-knife for said knife-stock, a cutting-block of relatively soft material arranged for penetration by said knife, a base fixed to said knife-stock adjacent the fixed frame of the machine, a stop-plate movably mounted on said base and adapted to engage the fixed frame of the machine, a spring arranged to outwardly move or project said stop-plate with respect to said base, inter-engaging means between said base and stop-plate for controlling the projecting movement of the latter, and a stop-screw adjustable in said base and arranged to engage and limit the inward movement of said stop-plate.

Signed at New York in the county of New York and State of New York this 12th day of March A. D. 1919.

CHARLES W. LOVELL.
